UNITED STATES PATENT OFFICE.

JOSEPH W. KIMMERLY, OF WARREN, ARIZONA.

SWITCH.

1,358,160.

Specification of Letters Patent. Patented Nov. 9, 1920.

Application filed March 25, 1920. Serial No. 368,538.

To all whom it may concern:

Be it known that I, JOSEPH W. KIMMERLY, a citizen of the United States, residing at Warren, in the county of Cochise and State 5 of Arizona, have invented certain new and useful Improvements in Switches, of which the following is a specification, reference being had to the accompanying drawings.

This invention relates to certain improvements in switches, and it is an object of the invention to provide a novel and improved device of this general character embodying a movable frog point which is operatively connected with the switch points so that the 15 position of the frog point is governed by the switch points and in a manner to produce a closed frog, thereby giving the wheels of the rolling stock a continuous rail on which to run during a switching operation.

20 The invention consists in the details of construction and in the combination and arrangement of the several parts of my improved switch whereby certain important advantages are attained and the device rendered simpler, less expensive and otherwise 25 more convenient and advantageous for use, as will be hereinafter more fully set forth.

The novel features of my invention will hereinafter be definitely claimed.

30 In order that my invention may be the better understood, I will now proceed to describe the same with reference to the accompanying drawings, wherein:

Figure 1 is a fragmentary view in top plan 35 and partly in section illustrating a switch constructed in accordance with an embodiment of my invention, the mechanism for throwing the switch points being diagrammatically indicated; and

40 Fig. 2 is a view in perspective of the frog point detached.

As disclosed in the accompanying drawings, R denotes the rails of the main line, and B the rails of the branch line, and with 45 which coact the switch points S. The points S are tied by the cross rod 1 whereby said points S move in unison and in the same general direction. M indicates diagrammatically any desired mechanism whereby the 50 requisite endwise movement may be imparted to the rod 1 for throwing the points S as desired.

F denotes a frog point coacting with the adjacent guard rails B' and R', and which 55 frog point is mounted for swinging movement relative to said guard rails, and for

which reason the point F is pivotally engaged at one end, as indicated at 2, with the frog A.

The pivoted end portion of the frog point 61 F is provided with an inwardly directed arm 3 terminating in a vertically disposed plate 4 having disposed therethrough an opening 5.

Loosely directed through the opening 5 65 is an end portion of a rod 6 disposed between the rails R and movable in a direction longitudinally thereof. The rod 6 at opposite sides of the plate 4 is provided with the stops or enlargements 7 and interposed 70 between each of said enlargements 7 and the plate 4 is an expandible member 8. As herein disclosed each of the members 8 comprises a coil spring encircling the rod 6.

The rod 1 at a point between the switch 75 points S is provided with an upstanding pin 9 which extends within a longitudinally disposed slot 10 produced in an arm a of a bell crank lever L. The heel of the bell crank lever L is pivotally mounted as at 11 for swinging movement and the rod 6 is pivotally engaged as indicated at 12 with the outer end portion of the second arm b of the bell crank lever L.

When the switch points S are thrown 85 through the medium of the mechanism M the bell crank lever imposes the desired strain or stress upon the rod 6 to throw the frog point F substantially in unison with and in the same general direction as the 90 switch points S so that a continuous rail is provided with the rolling stock when travelling over the main line or on to the branch or side line. It will be self-evident that the 95 tension of the member 7 is sufficient to impart the desired swinging movement to the point F through the medium of the arm 3 and at the same time compensates for any 100 inequality of the relative movements of the points S and the point F.

C denotes a casing or housing in which the rod 6, the bell crank lever L and the major portion of the arm 3 are contained so that the same are effectively protected 105 against the elements or the like, so that the desired operation of my improved switch is assured.

From the foregoing description, it is thought to be obvious that a switch constructed in accordance with an embodiment 110 of my invention is particularly well adapted for use by reason of the convenience and

facility with which it may be assembled and operated, and it will also be obvious that my invention is susceptible of some change and modification without departing from the 5 principles and spirit thereof, and for this reason I do not wish to be understood as limiting myself to the precise arrangement and formation of the several parts herein shown in carrying out my invention in practice except as hereinafter claimed.

I claim:

In combination with the rails of a main line and a branch line, switch points coacting therewith, means connecting the points 10 15 whereby the same move in unison and in the same general direction, a movable frog point, a laterally directed arm carried by

the frog point, a rod disposed longitudinally of the main rails, an operative connection between the first named rod and the second 20 named rod whereby endwise movement is imparted to the second named rod upon the throwing of the switch points, said second named rod being loosely disposed through the arm of the frog point, 25 and yieldable members carried by the second named rod at opposite sides of the arm of the frog point and contacting with said arm whereby the frog point is moved in unison with and in the same general direction as the 30 switch points.

In testimony whereof I hereunto affix my signature.

JOS. W. KIMMERLY.
